UNITED STATES PATENT OFFICE

147,217

DESIGN FOR A PENDANT OR SIMILAR ARTICLE

Oscar Guth, New York, N. Y.

Application January 26, 1946, Serial No. 126,008

Term of patent 3½ years

(Cl. D45—15)

To all whom it may concern:

Be it known that I, Oscar Guth, a citizen of Czechoslovakia, residing in New York, in the county of New York and State of New York, have invented a new, original, and ornamental Design for a Pendant or Similar Article, of which the following is a specification, reference being had to the accompanying drawings, forming a part thereof.

In the drawings:

Fig. 1 is a front elevational view of a pendant showing my new design.

Fig. 2 is a side view thereof, and

Fig. 3 is a sectional view on the line 3—3 of Fig. 1.

I claim:

The ornamental design for a pendant or similar article, as shown.

OSCAR GUTH.
